UNITED STATES PATENT OFFICE.

PHILIP LANG, OF CEDAR FALLS, IOWA, ASSIGNOR TO WAGNER MANUFACTURING COMPANY, OF CEDAR FALLS, IOWA.

ELECTROMECHANICAL BAR INTERLOCK FOR ELEVATOR DOORS.

Application filed September 24, 1925. Serial No. 58,366.

My invention relates to improvements in electromechanical interlocks for elevator doors.

The object of my invention is to provide 5 an electromechanical bar interlock in which the elevator doors are manually operated and closed, said interlock adapted to control the circuit to the controller on the elevator so that the elevator can not be started 10 when the door is open.

Another object of my invention is to provide a gravity latch hook, the weight of which will operate the circuit closer for controlling the circuit to the controller, 15 whereby a certain period of time transpires after the door is closed before the elevator can be started.

A further object of my invention is to provide a device of this character which can 20 be readily applied to any well known elevator doors and at the same time providing a simple, cheap and effective interlock adapted to accomplish the above mentioned objects and having certain details of structure 25 and combination of parts hereinafter more fully set forth.

In the accompanying drawings:—

Figure 1 is a plan view of my improved interlock.

Figure 2 is an end view.

Referring now to the drawings, 1 represents a plate supported by the elevator door and provided with three brackets 2, 3 and 4 in which is guided the gravity latch hook 5, 35 which has adjacent its upper end a lateral off set portion 6 having the vertical portion 7 provided with a hook 8. The combined switch box and latch box 9 is carried by the bracket 10 secured to the elevator shaft 11 in any desired manner, and is of the structure shown in Figure 2 of the drawings, so as to allow for the proper space 12 for the door hangers and tracks, which is not shown, as the same is well understood by those 45 skilled in the art. The casing 9 has in the end wall 13 an opening 14 through which the latch hook 8 passes, and when the latch hook is released it drops down in the position shown in full lines in Figure 1 of the drawings, and hooks over the end wall 13 and thus the elevator door is held closed. Arranged within the combined switch and latch box 9 is a plate 15 preferably made of bakelite which may be secured within the switch 50 box by screws passing through the rear wall

16 from the outside of the box. Leading into the switch box are the two terminals 17 and 18, leading from the controller and are secured to the flexible switch fingers 19 and 20 at 21 and 22; and said switch fingers 19 and 20 are spaced a considerable distance apart and have their free ends turned outwardly as indicated at 23. The gravity trigger 24 is pivoted between the front and rear walls of the switch box by means of the pivot 25 and said trigger 24 has an upwardly extending arm 26 which is bifurcated at its upper end and through which passes the fiber pin 27 upon which is mounted the brass contact roller 28. As shown in full lines in Figure 1, this roller passes between the switch fingers 19 and 20 which completes the circuit so that when the trigger is in the position shown in full lines Figure 1, the elevator circuit is closed and the elevator can 70 be started. Surrounding the fiber pin 27 on the outside of the steel roller 28 are fiber washers 29 which insulate the roller 28 from the bifurcated end 26 of the gravity trigger so that the circuit can not pass to said trigger. The fingers 19 and 20 as shown in the drawings are arranged in an arc of a circle struck on the center of the pivot 25 of the gravity trigger 24.

The gravity trigger 24 on the opposite 85 side of the pivot 25 is provided with the outwardly curved arm 30, which is engaged by the latch hook 8 when the bar 1 is raised, rocking said gravity trigger 24 on its pivot 25 and moving it in the position shown in 90 dotted lines in Figure 1. When in this position the circuit is broken and the door can be opened but the elevator can not be started. The door is then moved in the direction of the arrow, Figure 1, bringing the latch hook 8 through the opening 14 for releasing the door. When closing the door it will be seen that the latch hook 8 enters the opening 14 in the wall 13 of the switch box and when released drops by gravity so that the latch hook 8 engages the portion 31 of the gravity trigger rocking it upon the pivot 25, throwing the roller 28 between the contact fingers 19 and 20 so that the circuit is closed to the controller and the elevator can be 100 operated. By this structure it will be seen that after the elevator door is completely closed there will be a short period of time before the circuit is closed as the gravity latch has to be released and travel down- 110

wardly until the same engages the portion 31 of the gravity latch 24.

In order to open the door from the outside of the elevator shaft, I provide the 5 plate 1 with a slot 32, through which a key can be passed from the outside of the shaft and engage the lower end of the gravity latch bar 5 for raising it and releasing it.

The gravity trigger 24 is provided with a 10 rubber bumper or silencer 33 which is adapted to engage the wall of the latch box 9 and prevent any noise caused by the rearward movement of the trigger. The latch hook 5 is also provided with a rubber bumper or silencer 34 which engages the upper end of the guide bracket 2, and prevents the same from making any noise when it is released and travels downwardly.

Having thus fully described my invention what I claim is:—

1. A device of the character described comprising a combined latch and switch box carried by the elevator shaft, and having the terminals from the controller entering the 25 same, a gravity trigger mounted in said box and adapted to close the circuit between the terminals, and a vertically movable gravity latch hook and bar carried by the elevator door and adapted to enter the switch box 30 and close the circuit when moved downwardly by gravity and adapted to open the circuit when moved upwardly preparatory to withdrawing the gravity latch hook from the switch box.

2. A device of the character described comprising a switch and latch box supported by the elevator shaft, spring fingers within said box and connected to the terminals of the elevator controller, a gravity trigger pivoted in said box and having an arm adapted to pass between said switch fingers and closing the circuit, and a gravity latch hook and bar adapted to enter said box and lock with a wall thereof and adapted to 45 move the gravity trigger so that the circuit is closed and said gravity latch hook and bar adapted to move said gravity trigger to break the circuit when the gravity latch is raised.

3. A device of the character described comprising a switch and latch box carried by the elevator shaft, spring switch fingers mounted therein, and connected to the terminal of the controller, a pivoted latch trigger mounted in the box and having a roller carried by one end and insulated therefrom and adapted to pass between the switch fingers, the said gravity trigger having two arms on the opposite side of the pivot, and 55 a gravity latch hook and bar having a hooked end and adapted to pass through an opening in the box and when lowered engage one of the arms to rock the trigger to bring

the roller between the spring switch fingers for completing the circuit, and when the 65 latch hook and bar is raised engaging another arm for rocking the trigger on the pivot and throwing the roller from between the switch fingers.

4. A device of the character described 70 comprising a combined switch and latch box carried by the elevator shaft, a pivoted trigger for opening and closing the circuit, a rubber silencer carried thereby and adapted to engage the latch box, and a gravity latch 75 hook and bar carried by the elevator door and adapted to enter the same and lock the door thereto and close the circuit by a downward movement thereof, and a rubber silencer carried by the gravity latch hook and bar 80 for silencing the bar when it reaches the downward limit of movement.

5. A device of the character described comprising a combined latch and switch box, and having the terminals from the controller 85 entering the same, a gravity trigger intermediately pivoted in said box, a gravity latch hook and bar for operating the trigger, a contacting member carried by the gravity trigger, and spring contacts 90 arranged in an arc of a circle struck on the center of the pivot of the gravity latch and connected to the terminals of the controller, whereby the contact of the trigger is forced between the spring contacting members. 95

6. A device of the character described comprising a latch and switch box having the terminals from the controller entering the same, a gravity trigger pivoted in the box intermediate its ends, and having one 100 end bifurcated and the opposite end carrying an insulated contacting member, and a gravity latch hook and bar adapted to enter the switch box between the bifurcated end of the trigger, and spring contacting members 105 within the box and connected with the terminals of the controller and arranged in an arc of a circle struck from the pivot of the gravity trigger.

7. A device of the character described 110 comprising a combined latch and switch box carried by the elevator shaft and having the terminals from the controller entering the same, a gravity trigger intermediately pivoted within said box, a gravity latch hook 115 and bar carried by the elevator door and adapted to enter the switch box and rock the gravity trigger on its pivot, and spring contacting members within the switch box and connected to the controller terminals and arranged in an arc of a circle struck on the pivot of the gravity trigger. 120

In testimony whereof, I have signed this specification.

PHILIP LANG.
